WALKING SPACE VEHICLE TOY

Arthur R. Gorfain, Fair Lawn, N.J., assignor to Cragstan
Industries, Inc., New York, N.Y.

Filed Apr. 15, 1970, Ser. No. 22,432

Term of patent 14 years

Int. Cl. D21—02

U.S. Cl. D34—15

FIG. 1

FIG. 2

FIG. 6

FIG. 7

FIG. 1 is a front perspective view of a "Walking Space Vehicle Toy" showing my new design; and FIG. 2 is a rear perspective view thereof; FIG. 3 is a side elevational view thereof; FIG. 4 is a front elevational view thereof; FIG. 5 is a rear elevational view thereof; FIG. 6 is a top plan view thereof; and FIG. 7 is a bottom plan view thereof.
I claim:

The ornamental design for a walking space vehicle toy, substantially as shown.
